UNITED STATES PATENT OFFICE.

ALBERT G. ELVIN, OF SOMERVILLE, NEW JERSEY.

FURNACE-DOOR DEVICE.

1,190,529.

Specification of Letters Patent. Patented July 11, 1916.

Application filed October 5, 1914. Serial No. 865,010.

To all whom it may concern:

Be it known that I, ALBERT G. ELVIN, a citizen of the United States, residing at Somerville, in the county of Somerset and 5 State of New Jersey, have invented a certain new and useful Improvement in Furnace-Door Devices, of which improvement the following is a specification.

This invention relates to apparatus for 10 operating doors of boiler furnaces, and particularly fire doors for locomotive boilers, the principal object being to provide an improved combined fluid pressure and hand operated door device of the type having a 15 horizontal cylinder and piston and a pair of pivoted fire doors adapted to swing laterally and vertically and to close by gravity.

According to my improvement, a pivoted hand lever is provided having a short 20 curved arm adapted to engage the piston, or a pin attached thereto, and move the piston horizontally in the cylinder when the long arm of the lever is turned downward, thereby operating the door as if fluid pressure 25 were admitted to the cylinder.

In the accompanying drawing: Figure 1 is a view, partly in front elevation and partly in vertical section showing the upper portion of a pair of doors and operating mechanism embodying my improvement; Fig. 2, a vertical transverse section, taken substantially on the line 2—2 of Fig. 1; Fig. 3, an end elevation of the same; and Fig. 4, an elevation of the latch device with 35 the lever indicated in section.

According to the construction shown in the drawing, my improvement is illustrated in connection with a pair of furnace doors, 5 and 5^a, mounted to swing laterally and 40 vertically on the respective pins, 6 and 6^a, supported in the door frame, 7, and operated by a fluid pressure motor comprising a horizontal cylinder, 3, having a flange, 3^a, also supported on the bolts or pins, 6^a, and 45 containing a piston, 9, carrying a pin, 11, extending through a slot, 12, in the side of the cylinder and connected by a link, 10, with the upper portion of one of the doors, such as 5^a, above the pivot pin, 6^a. The 50 doors are also provided with intermeshing segmental gears, 4 and 4^a, whereby both doors are caused to swing together in opening and closing. The link, 10, may be provided with an open slot in its end in order 55 that the link may be quickly disconnected from the piston whenever it becomes neces-

sary to remove the cylinder. The link may then be turned upward to the position indicated in dotted lines, Fig. 1.

According to my improvement, a hand 80 lever, 13, is pivoted on the frame, preferably on the door pivot pin, 6, and is provided at one end with a short curved arm, 13^a, extending upward through a slot, 3^b, in the cylinder, and into a slot or recess, 9^a, 85 formed in the piston, 9, where it engages the pin, 11, for moving the piston. In its normal position, the hand lever extends upward and outward in a plane substantially parallel with that of the doors, and is adapted 70 to be turned downward around the side of the door frame in the opening movement, during which the curved arm engages the pin, 11, and forces the piston outward, thus 75 opening the doors in the same manner as when fluid pressure is admitted to the cylinder.

For the purpose of holding the hand lever in its different positions, a latch device, 15, is supported on the cylinder flange, and has 80 notches, 18, 19, and 20, for holding the lever in its normal closed position, in the partial open position, and in the full open position, respectively. A spring plunger, 17, mounted 85 in a recess in the frame of the latch device is adapted to bear against the side of the lever when in its normal closed position, and prevent the same from slipping out of the notch, 18. A safety latch, 21, having a handle, 22, is pivotally mounted in the lower 90 part of the latch frame and is adapted to be turned up to the position shown in Fig. 4, and bear against the side of the lever, 13, when it is desired to lock the same in the notch, 20, with the doors in the full open 95 position. This is used principally for the purpose of preventing accidental closing of the doors when the engine is in the shop and the doors are set to the full open position for 100 inspection and repairs in the firebox.

When operating manually, the leverage of the hand lever gradually increases as it is turned downward from its normal position, since the pin, 11, slides along the upper curved surface of the arm, 13^a, and the distance between the centers of the pins, 6 and 11, gradually diminishes until the door reaches the full open position, thus manually increasing the power of the hand lever. In 105 moving the hand lever from its normal position it is first pulled forward to compress the spring plunger and release the lever from 110

the latch, 18. The lever is then turned downward to either one of the other notches desired, during which movement the short curved arm, 13^a, engages the pin, 11, of the piston and forces the same outward thus opening the doors, in the same manner as when fluid pressure is admitted to the cylinder to actuate the piston. When the piston is actuated by air or other fluid under pressure, however, the hand lever does not move as the same is held in its normal position while the elongated recess, 9^a, in the piston, 9, allows for the movement of the piston without actuating the arm, 13^a, of the hand lever. This comprises a simple and convenient mechanism for operating the doors either manually or by fluid pressure as may be desired.

Having now described my invention, what I claim as new and desire to secure by Letters Patent is:

1. In a furnace door device, the combination of a pair of doors mounted on pivots to swing laterally and vertically, a cylinder, 25 a piston therein, a pin and link connecting the same to one of said doors, means opera-

tively connecting said doors, and a hand lever mounted at an intermediate point on one of the door pivots and having a curved arm at its end engaging said pin for manually operating the piston. 30

2. In a furnace door device, the combination of a pair of doors mounted on pivots to swing laterally and vertically, a horizontal cylinder, a piston therein, a pin and link connecting the same to one of said doors, means operatively connecting said doors, said piston having a slotted recess formed therein, and a hand lever having a curved arm extending into said recess and engaging 35 said pin for manually operating the piston. 40

3. In a furnace door device, the combination of a door pivoted to swing laterally and vertically, a hand lever and connections for manually operating the door, a latch frame having a notch for holding the lever in the full open position, and a movable safety latch for locking the lever in said notch. 45

ALBERT G. ELVIN.
